ATTYS.

Patented June 7, 1927.

1,631,587

UNITED STATES PATENT OFFICE.

ERNEST W. GATES, OF NEEDHAM, MASSACHUSETTS.

PUZZLE OR GAME.

Application filed October 12, 1926. Serial No. 141,050.

This invention relates to a puzzle symbolizing a broadcasting radio station, a receiving radio station, the phenomenon known as "static", and signals transmitted from the 5 broadcasting station to the receiving station, the feat to be accomplished being the transmission of the signals through static to the receiving station, and the visible announcement of a call at the latter.

10 The invention is an improvement on the symbolic puzzle disclosed by my Patent No. 1,600,727, dated September 21, 1926, and has for its chief object to increase the difficulty of accomplishing the feat for which the puzzle is intended.

15 Another object is to provide a puzzle symbolizing a central broadcasting station and a plurality of receiving stations located in different directions from the broadcasting station.

Other objects will be evident from the following description.

Of the accompanying drawings forming a part of this specification,

20 Figure 1 is a top plan view of a symbolic puzzle embodying the present improvements, a portion being broken away.

Figure 2 is a top plan view, showing the portion broken away from Figure 1.

25 Figure 3 is a section on line 3—3 of Figure 1.

Figure 4 is a perspective view, showing one of the annunciator members.

The same reference characters indicate the 30 same parts in all of the figures.

The improved puzzle resembles the puzzle disclosed by my above-mentioned patent, in that it comprises a base 12, adapted to be held at various inclinations by the hands of a 35 user, and to permit the rolling of balls on its upper surface when the base is inclined, a depression 14 in the base, symbolizing a broadcasting station, a plurality of pockets 15 in the base, a continuous curb 16, surrounding the portion of the base containing 40 the depression and the pockets, a plurality of loose balls 13, corresponding in number to the pockets, and symbolizing radio signals, inscribed annunciator members 17, associated with the pockets, each member being 45 normally concealed and movable to a displayed position by a ball arrested by a pocket, and baffle members 18, symbolizing static, projecting above the base and arranged to 50 cause each ball to move in an irregular course from the depression 14 to a pocket 15.

In the puzzle of my former patent the depression is located near one end of the base and the pockets are arranged in a group near the opposite end. The manipulation of 60 the base whereby the balls are caused to roll from the depression to the pockets is relatively simple and involves a primary inclination of the base to cause the balls to roll toward the group of pockets and various 65 secondary inclinations to cause the balls to pass the baffle members and enter the pockets. To increase the difficulty of accomplishing the intended feat, and to enable the pockets and annunciator members to symbolize a plurality of receiving stations, I have located 70 each pocket in a different radial direction, relative to the depression, from the others, so that the manipulation of the base whereby one ball is caused to roll from the depression 75 to a given pocket differs from that required to cause any other ball to roll from the depression to any other pocket. In other words, assuming that there are four pockets and four balls, four different manipulations 80 of the base are required, each involving a primary inclination of the base to cause a ball to roll from the depression toward a pocket, and various secondary inclinations to cause the ball to pass the baffle members 85 and enter the pocket which is its goal, each pocket and the accompanying annunciator member symbolizing a different receiving station.

I have also arranged the baffle members so 90 that they cause each ball to take a different irregular course while on its way from the depression to the pocket which is its goal, from the course taken by any other ball.

The depression 14 is located at the center 95 of the base, and the pockets 15 are grouped around the depression, so that the radial direction of each pocket from the depression 14, differs from that of each of the other pockets. A suitable arrangement of the baffle members whereby they cause each ball to take a different irregular course from that of any other ball, is shown by Figure 1. The courses of the several balls will be understood by the numbered arrows. The arrows 100 1 indicate the course of a ball from the central depression to the pocket 15, shown at the left of the figure. The arrows 2 indicate the course of a ball from the depression to the pocket 15, shown at the bottom of Figure 1. The arrows 3 indicate the course of a ball 105 from the depression to the pocket 15, shown

at the right of Figure 1. The arrows 4 (Figures 1 and 2) indicate the course of a ball from the central depression to the pocket 15 shown at the top of Figure 1.

5 Owing to the number of different inclinations of the base required to cause the balls to move in the courses shown, the feat is quite difficult of accomplishment. The difficulty is increased by additional baffle members 18, forming by-passes or hazards into which the balls are liable to roll, as indicated by the dotted arrows in Figure 1.

The balls are preferably of different sizes as shown by Figure 1, and the baffle members are arranged to provide exits 1^a, 2^a, 3^a and 4^a from the depression 14, preferably of different widths, the widths of the exits corresponding to the diameters of the balls. The largest ball can pass only through the 20 exit 4^a, the next smaller ball can pass through the exits 4^a and 3^a, but not through the others. The next smaller ball can pass through the exits 4^a, 3^a and 2^a but not through the exit 1^a which is negotiable only 25 by the smallest ball. When the feat is properly accomplished according to directions which may be furnished with the outfit, there must be only one ball at each receiving station and each ball must have passed 30 through a predetermined course to the pocket which is its prescribed goal.

The target 17 of each annunciator is preferably turned edgewise upward, as shown by Figures 3 and 4, from the pivoted lever 35 17^a by which it is carried, so that when a ball enters the pocket 15, the inscribed face of the target stands vertically above the base.

The base is provided, as heretofore, with 40 a glass cover 22, and with openings 23 in which the targets 17 are vertically movable. To indicate distances between the broadcasting station and the receiving stations, I provide the base with outline markings constituting a map as shown by Figure 1. Said markings may be printed on the base by lithography, or otherwise, before the baffle members are applied to the base. The baffle members may be strips of sheet metal, or 45 other material, fixed in any suitable manner to the base, or they may be composed of wire.

The base may be provided, as indicated 50 by the drawing of my above mentioned patent, with markings at the broadcasting and receiving stations representing antennae, and with zig zag markings associated with the baffle members. To avoid confusion I have omitted these markings from the present drawing. I am not limited to the number 55 of the receiving stations and the balls, and to the arrangement of the baffle members, shown by the drawing.

I claim:

60 1. A symbolic puzzle comprising a base

on which balls may roll when the base is manipulated to incline it, a central depression in the base symbolizing a broadcasting station, a plurality of pockets in the base, grouped around the central depression, a 70 continuous curb surrounding the portion of the base containing the depression and the pockets, a plurality of loose balls corresponding in number to the pockets and symbolizing radio signals, inscribed annunciator 75 members associated with the pockets, each member being normally concealed and movable to a displayed position by a ball arrested by a pocket, each pocket and the accompanying annunciator member symbolizing 80 a receiving station, and baffle members symbolizing static, projecting above the base and arranged to cause each ball to move in an irregular course from the central depression to a pocket, and to cause each ball to take 85 a different course from that of any other ball, the relative arrangement of the central depression and the pockets being such that the manipulation of the base required to cause the movement of a ball to either 90 pocket, differs from that required to cause the movement of a ball to any other pocket.

2. A symbolic puzzle as specified by claim 1, the baffle members including hazards 95 liable to deflect the ball from its predetermined course.

3. A symbolic puzzle comprising a base having a central depression symbolizing a broadcasting station, a plurality of pockets and annunciator members associated therewith, each pocket and annunciator member symbolizing a receiving station located in a different radial direction relative to the broadcasting station from the other receiving stations, baffle members between the 105 broadcasting station and each receiving station, and loose balls movable by manipulations of the base from the broadcasting station to the receiving stations.

4. A symbolic puzzle comprising a base 110 having a central depression symbolizing a broadcasting station, a plurality of pockets and annunciator members associated therewith, each pocket and annunciator member symbolizing a receiving station located in a 115 different radial direction relative to the broadcasting station from the other receiving stations, baffle members between the broadcasting station and the receiving stations, and loose balls movable by manipulations of the base from the broadcasting station to the receiving stations, the base being provided with a map indicating distances between the broadcasting station and the receiving stations.

5. A symbolic puzzle comprising a base having a central depression symbolizing a broadcasting station, a plurality of pockets and annunciator members associated therewith, each pocket and annunciator member 120 125 130

symbolizing a receiving station located in a different radial direction relative to the broadcasting station from the other receiving stations, baffle members between the

5 broadcasting station and the receiving stations, arranged to form exits of different widths from the central depression, and loose balls of different diameters correspond-

ing to the widths of the exits, and movable by manipulations of the base from the 10 broadcasting station to the receiving stations.

In testimony whereof I have affixed my signature.

ERNEST W. GATES.
